TOY TELEPHONE

Harold D. Allen, East Hampton, Conn., assignor
to The Gong Bell Manufacturing Company,
East Hampton, Conn., a corporation of Con-
necticut

Application June 4, 1931. Serial No. 542,075

4 Claims. (Cl. 46—46)

My invention relates to that class of toys designed for the amusement of children in assuming telephonic operations, and an object of my invention, among others, is to simplify the construction and also to arrange the members in units so that each unit after being assembled may be secured in toto to the base or other parts of the toy.

One form of a toy telephone embodying my invention, and in the construction and use of which the objects herein set out, as well as others, may be attained is illustrated in the accompanying drawing, in which—

Figure 1 is a side view of my improved telephone showing the calling unit separate from the base.

Figure 2 is a similar view but showing the base and calling unit in central section on a plane denoted by the dotted line 2—2 of Figure 3, and 20 with the upper part of the standard broken off.

Figure 3 is a view in horizontal section on a plane denoted by the dotted line 3—3 of Figure 1.

Figure 4 is a view in section through the calling unit on a plane denoted by the dotted line 25 4—4 of Figure 2.

As a convenience in manufacture and to reduce the cost of production it has been found desirable to assemble toys of the class herein described in separate units, the parts of each unit 30 being assembled as a complete structure so far as the unit is concerned. This method of construction also enables toys of this class to be handled by the five and ten cent stores, as the units may be sold for the regulated price and afterward 35 may be readily assembled by the purchasers of the units.

Such a toy telephone is illustrated and described herein in which, in the drawing, the numeral 5 denotes the base, that is of dish shape, 40 stamped from sheet metal in imitation of the regular desk type of telephone, and particularly of the so-called French type. This base has a flat portion or table 6 on which a calling unit is removably mounted, there being a hole 7 to 45 receive a projecting part of the calling unit and slots 8 through which clips projecting from the calling unit are inserted.

Said calling unit comprises a base plate 9 that 50 may be of any desired shape, that herein shown being oblong with rounded ends and having clips 10 insertable through the slots 8 and adapted to be bent over to secure the base plate in position on the table 6. A shaft 11 is supported by blocks 55 12—13, said blocks being located on opposite sides of the plate 9. A ratchet wheel 14 is mounted on

said shaft between the blocks 12 and 13, a gong 15 is mounted on the shaft on the opposite side of the block 13 from the ratchet wheel and an actuating thumb nut 16 fitting the threaded end of the shaft secures the shaft, blocks, ratchet 60 wheel and gong to the plate 9, there being play enough between said blocks, ratchet wheel and plate to permit free turning movement of said parts and the gong independently of said plate.

The teeth of the ratchet wheel 14 engage the 65 teeth of a pallet 17 pivotally mounted on the plate 9 and having a striker arm 18 carrying a striker 19 positioned to strike the rim of the gong 15.

A standard 20 is adapted to be secured to the base 5, as by means of a rod 21 extending through 70 a bracket 22 adapted to receive the hand set 23 of the so-called French type of telephone shown herein, although substantially the same arrangement may be made for an ordinary desk set of telephone instruments. The rod 21 may be se- 75 cured as by means of a head on one end and a nut fitting the opposite and threaded end of said rod.

This standard and bracket may be arranged as a unit to be separately secured to the base, 80 thereby creating three units, to wit, a telephone unit comprising the standard and hand set bracket, a base and a calling unit, anyone of which in combination with another, may be disposed for sale as separate articles of merchandise. 85

In accordance with the provisions of the patent I have described the principles of operation of my invention together with the device which I now consider to represent the best embodiment thereof; but I desire to have it understood that 90 the device shown is only illustrative, and that the invention may be carried out by other means and applied to uses other than those above set out.

I claim:

1. A toy telephone including a base, a base plate arranged for removable attachment to said base, a shaft rotatably mounted in said base plate, a bearing block through which said shaft extends, a gong secured to said shaft, and striking mechanism mounted on said plate within said 95 gong.

2. A toy telephone including a base, a base plate arranged for removable attachment to said base, a shaft rotatably mounted in said base plate, a bearing block arranged on each side of the base plate and through which said shaft extends, a gong secured to said shaft, and striking mechanism mounted on said plate within said gong. 105

3. A toy telephone including a base having an enlarged hole therein, a base plate arranged for 110

removable attachment to said base, a shaft rotatably mounted in said base plate, a bearing block located on the under side of said base plate and extending through the hole in said base, 5 a bearing block arranged on the upper side of the base plate, said shaft extending through said bearing blocks, a gong secured to said shaft, and striking mechanism mounted on said plate within said gong.
10 4. A toy telephone including a base having a flat table on its upper surface with an opening through said table and also clip openings therethrough and a signalling unit and a telephone

unit made to simulate regular telephone members, said signalling unit comprising a plate fitted flatly against said table and having fastening clips projecting therefrom, a shaft projecting through said plate, and a dialling and signalling mechanism secured to said plate constituting a unitary structure such that it may be assembled as a unit for attachment to said table by insertion of said shaft through said opening in the base in the table and by over-turning said clips on said plate 85 to secure it to the table.
